UNITED STATES PATENT OFFICE

LOWELL W. SHIELDS, OF ROCHESTER, NEW YORK, ASSIGNOR TO HICKOK MANUFACTURING COMPANY, INC., OF ROCHESTER, NEW YORK, A CORPORATION OF NEW YORK

BEAD LINE LEATHER BRACE

Application filed August 1, 1932. Serial No. 627,203.

The invention relates to bead line leather braces.

The object of the present invention is to improve the construction of leather braces and to provide simple, practical and comparatively inexpensive leather braces of strong and durable construction having body portions provided with a raised ornamental bead extending longitudinally of the body portion and adapted to be made of a color contrasting with that of the body portion so that the leather braces will present a highly ornamental and attractive appearance.

With these and other objects in view, the invention consists in the novel construction, combination and arrangement of parts hereinafter fully described, illustrated in the accompanying drawing, as pointed out in the claims hereto appended, it being understood that various changes in the form, proportion, and minor details of construction, within the scope of the claims, may be resorted to without departing from the spirit or sacrificing any of the advantages of the invention.

In the drawing:—

Figure 1 is an elevation of a pair of bead line leather braces constructed in accordance with this invention;

Figure 2 is an enlarged detail view of a portion of one of the straps or body portions of the braces;

Figure 3 is a transverse sectional view on the line 3—3 of Figure 2, illustrating the arrangement of a cord for supporting the bead of the insert.

Figure 4 is a similar view showing a strip of material for forming the core of the bead.

Figure 5 is a transverse sectional view of the body portion showing the bead supported by stitching.

In the accompanying drawing in which is illustrated the preferred embodiment of the invention, 1 indicates a pair of suspenders or braces having each of its body portions 2 constructed of leather and provided at the front with a longitudinal ornamental bead 3. The body portion consists of a strip 4

of leather folded along longitudinal lines equi-distant of its center to provide side flaps 5 extending inwardly from the side edges of the body portion and terminating short of the center line thereof to provide an intervening longitudinal space 6 in which the bead 3 is arranged and through which the said bead 3 projects. The bead 3 projects slightly beyond the outer faces of the flaps 5 and is designed to be of a color contrasting with the color of the flaps so that the body portion will present an ornamental and attractive appearance.

The bead is formed by an insert 7 consisting of a strip of leather or other material of a width to extend entirely across the body portion and to form the bulging bead 3 and it is composed of the said bead 3 and side portions which are secured beneath the flaps 5 and between the same and the body portion of the leather strip by cement or other adhesive material and by lines of stitching 8 located at opposite sides of the bead in spaced relation to the same and the inner edges of the flaps and piercing the latter, the side portions of the insert and the body portion of the leather strip as clearly illustrated in Figure 3 of the drawing. The side portions of the insert are concealed beneath the side flaps of the main leather strip 4.

In Figure 3 of the drawing the outwardly bulging portion or bead 3 of the insert 7 is supported by a core consisting of a cord 9 which is adapted to maintain the bead in its curved sectional contour and prevent collapsing of the bead. The cord 9 may be secured in the bead by adhesive material if desired.

In Figure 4 of the drawing the bead 10 is supported by a core consisting of a strip 11 of material composed of side portions and a central bead or bulging portion 12 adapted to substantially fill the bead 10 of the strip 13 and having its side portions secured in contacting relation by means of a line of stitching 14 which also passes through the sides of the bead 10 at a point below or in rear of the outer faces of the side flaps 15 of the leather strip 16. In practice the strip

13 which is exposed in the space between the flaps 15 and which is bulged to form the bead 10 will be of thinner material than the core forming strip. The side portions 5 of the insert 13 and the side portions of the strip 11 are secured together and to the strip 16 by cement or other suitable adhesive material and also by lines of stitching 17 located at opposite sides of the central bead.

In Figure 5 of the drawing the bead or bulged portion 18 of the insert 19 has its sides secured in contacting relation by means of a line of stitching 20 located below or in 15 rear of the plane of the outer faces of the side flaps 21 of the leather strip 22. The insert consists of a strip of leather or other suitable material secured between the side flaps 21 and the body portion of the strip 22 by cement or other suitable adhesive material and also by lines of stitching 23 located 20 at opposite sides of the bead 18 and piercing the flaps 21, the insert 19 and the body portion of the leather strip 22.

25 What is claimed is:

1. Braces having body portions each comprising a strip of material having its side portions folded inwardly along longitudinal lines forming longitudinal side flaps 30 spaced apart to provide an intervening space, and an insert consisting of a strip of material secured within the body portion and having a bead arranged in and projecting through the space between the said flaps. 35 2. Braces having body portions each comprising a strip of material having its side portions folded inwardly along longitudinal lines forming longitudinal side flaps spaced apart to provide an intervening 40 space, and an insert composed of a bead and side portions, the bead being arranged in and projecting through the opening between the side flaps and the side portions of the insert being secured beneath the said 45 side flaps and concealed by the same.

3. Leather braces having a body portion comprising a strip of leather having its side portions folded inwardly along longitudinal lines equi-distant of its center forming longitudinal side flaps spaced apart at the center of the strip to provide a central intervening space, and an insert consisting of a strip of material provided with a central bulging portion forming a bead arranged 50 55 in and projecting through the central space between the side flaps, the side portions of the insert being secured beneath the side flaps.

4. Leather braces having a body portion 60 comprising a strip of leather having its side portions folded inwardly along longitudinal lines equi-distant of its center forming longitudinal side flaps spaced apart at the center of the strip to provide a central intervening 65 space, and an insert consisting of a strip of

material provided with a central bulging portion forming a bead arranged in and projecting through the central space between the side flaps, the side portions of the insert being secured beneath the side flaps, and a core disposed longitudinally of the bead and extending into and supporting the same to prevent the bead from collapsing. 70

5. Leather braces having a body portion comprising a strip of leather having its side portions folded inwardly along longitudinal lines equi-distant of its center forming longitudinal side flaps spaced apart at the center of the strip to provide a central intervening space, and an insert consisting of a strip of material provided with a central bulging portion forming a bead arranged in and projecting through the central space between the flaps, the side portions of the insert being secured beneath the side flaps, and a core consisting of a cord arranged within the bead and preventing the same from collapsing. 75 80 85

6. Leather braces having a body portion comprising a strip of leather having its side portions folded inwardly along longitudinal lines equi-distant of its center forming longitudinal side flaps spaced apart at the center of the strip to provide a central intervening space, and an insert consisting of a strip of material provided with a central bulging portion forming a bead arranged in and projecting through the central space between the flaps, the side portions of the insert being secured beneath the side flaps, and a core consisting of a strip of material extending across the body portion interiorly thereof and having a bead arranged within the said bead to prevent the latter from collapsing. 90 95 100 105

7. Leather braces having a body portion comprising a strip of leather having its side portions folded inwardly along longitudinal lines equi-distant of its center forming longitudinal side flaps spaced apart at the center of the strip to provide a central intervening space, and an insert consisting of a strip of material provided with a central bulging portion forming a bead arranged in and projecting through the central space between the flaps, the side portions of the insert being secured beneath the side flaps, and a core consisting of a strip of material arranged within the body portion and composed of side portions and a central longitudinal bulging portion forming a bead arranged within the said bead, and a line of stitching located interiorly of the body portion and piercing the sides of both of said beads for securing the same together. 110 115 120

8. Leather braces having a body portion consisting of a strip of leather folded longitudinally at spaced points to form side flaps, the latter being extended inwardly and spaced apart at their inner edges to form an 125 130

intervening opening, an insert consisting of a strip of material secured within the folded portions of the leather strip and having a longitudinal bulging portion forming a bead 5 arranged in and projecting through the space between the side flaps, and a line of stitching piercing the sides of the bead and securing the same together.

9. Leather braces having a body portion 10 comprising a strip of leather folded along longitudinal lines at spaced points to provide inwardly extending side flaps the latter being spaced apart to form an intervening space, and an insert consisting of a strip of 15 material having a central longitudinal bulged portion forming a bead arranged in and extending through the space between the side flaps, and means for securing the insert within the leather strip consisting of adhesive material and lines of stitching located at opposite sides of the bead and piercing the side flaps, the insert and the body portion 20 of the leather strip.

In testimony whereof I have hereunto set 25 my hand.

LOWELL W. SHIELDS.
